GAS GENERATOR

Lászlo de Csaby, Tulsequah Township, British Columbia, Canada

Application November 9, 1939, Serial No. 303,679

21 Claims. (Cl. 261—12)

This invention relates to a gas generator particularly for use with internal combustion engines.

An object of the present invention is the provision of a device for generating a dry gas from liquids, such as gasoline, crude oil and other liquids of an explosive nature.

Another object is the provision of a gas generator in which the liquid supplied thereto is divided up into its finest molecular state.

Another object is the provision of a device for generating gas from liquid fuels in a simple and extremely efficient manner.

A further object is the provision of a gas generator for use with internal combustion engines, adapted automatically to adjust itself to the speed of the engine.

A further object is the provision of a gas generator for use with internal combustion engines, which is capable of supplying sufficient vaporized fuel for starting purposes and which thereafter automatically adjusts itself to operate at the maximum efficiency in relation to the speed of its engine.

A still further object is the provision of a device adapted completely to vaporize liquid fuel for internal combustion engines without employing or interfering with the suction of the engine for this purpose.

In the applicant's co-pending application S. N. 230,344, filed September 16, 1938, is shown a gas generator having a drum rotatably mounted in a casing forming a vaporizing chamber therebetween having a discharge outlet, means for supplying fuel and air to the chamber wherein said fuel is vaporized, and means for directing the vaporized fuel to the exhaust manifold of an engine, said last-mentioned means being a plurality of spiral passages.

The present invention differs from the above application in that the drum is movable in the chamber to regulate the size of the latter in relation to the speed of rotation of the drum, and means is provided for selectively supplying air to the chamber and for varying the quantity of the air in relation to the speed of the drum.

With the above and other objects in view, the present invention consists essentially of a gas generator for internal combustion engines, comprising a casing, a corrugated drum rotatably mounted in the casing, a vaporizing chamber formed between the drum and the casing, said chamber communicating with the intake manifold of the engine, means for rotating the drum, means for moving the drum back and forth in

the chamber to regulate the size of the vaporizing chamber in relation to the speed of the engine, and means for supplying fuel and air to the chamber wherein said fuel is vaporized, as 5 more fully described in the following specification and illustrated in the accompanying drawings, in which

Figure 1 is a longitudinal section taken through the gas generator,

10 Figure 2 is a front elevation of the generator with the drum and casing removed, part of the front wall and heating plate being broken away,

Figure 3 is an enlarged, fragmentary detail of the fuel supply valve mechanism,

15 Figure 4 is a detail of the valve, taken on the line 4—4 of Figure 3,

Figure 5 is an enlarged detail of a check valve,

Figure 6 is a side elevation of the vaporizing drum,

20 Figure 7 is a longitudinal section through an alternative form of the invention, with the drum and casing removed, and

Figure 8 is a view similar to Figure 1 of another alternative, with the fuel and air valve mechanism removed.

Referring more particularly to the drawings, 10 is a circular housing having front and rear walls 11 and 12 with a relatively large opening 13 and a smaller opening 14 formed in said front and rear walls, respectively, centrally thereof. An intake pipe 15 having a control valve 16 therein, communicates with the interior of the housing 10 at the bottom thereof while diametrically opposite said pipe, a discharge pipe 17 communicates at one end with the interior of the housing, the opposite end of the discharge pipe being provided with a flange 18 for connection with the intake manifold of an internal combustion engine (not shown). The discharge pipe 17 is formed with a restriction or Venturi passage 20 adjacent its lower end and with a throttle valve 21 above said restriction or passage.

A ring or circular partition 22 mounted in the housing 10, is spaced from and concentric with the peripheral wall 23 thereof, to form passages 24 and 25 extending from the intake pipe 15 to the discharge pipe 17. A hollow jet or nozzle 26 formed on the ring 22 and communicating with the space bounded thereby, projects into the discharge pipe 17 and is adapted to discharge into said pipe at the Venturi passage 20. This jet or nozzle is provided with a check valve 27 adapted to prevent fuel or air from passing back through the jet or nozzle into the space within the ring 22. A plurality of spirally disposed par-

titions 28 are mounted in the housing 10 and form a plurality of spiral passages 30, said passages extending from their entrances 31 outwardly in a spiral and terminating at their outlets 32 adjacent to but within the ring 22. The partitions are arranged in such a manner that the entrances 31 are smaller than the outlets 32 so that each passage 30 is actually tapered and increases in size from its entrance to its outlet.

The front wall 11 is preferably saucer-shaped so that, in cross section, it slopes inwardly from the opening 13 toward its periphery, see Figure 1. This wall is provided with drain openings 33 and 34 each having a drain plug 35 therein. The opening 33 is located near the ring 22 while the opening 34 is situated closer to the central opening 13 and a shoulder 36 separates said openings.

A sleeve 37 is formed on the wall 12 of the housing and extends inwardly from the opening 14. A bushing 38 is fitted inside the said sleeve and a hollow drive shaft 40 is journaled in the bushing and extends beyond each end thereof. A relatively broad gear 41 (see Figure 7) is mounted on the outer end of the shaft 40 and a conical vaporizing drum 42 is mounted on the other end of said shaft, with the base thereof projecting into the central opening 13 of the front wall 11 of the housing. The gear 41 is adapted to mesh with another gear (not shown) which is turned by the engine in any desired manner. to rotate the vaporizing drum. This drum may be connected for rotation to the engine in any suitable manner or it may be turned by means of an electric motor, the speed of operation of which is controlled by the engine. The main thing is that the speed of the drum is controlled by the engine so that its speed of rotation increases or decreases with a corresponding change of speed of the engine.

The drum 42 is provided with a hub 43 carried by the shaft 40, forming a chamber 44 within the drum, in which an electrical heating coil 45 is mounted. Leads 46 extend outwardly from the coil 45 through the shaft 40 to a suitable source of electrical supply, suitable means (not shown) being provided for permitting the coil to rotate without entangling the leads. A plurality of fan blades 47 extend outwardly from the base of the drum 42 approximately to the rear wall 12 of the housing, said blades overlapping the entrances 31 of the spiral passages 30. A spiral rib 48 is formed on the outer surface of the drum 42 and extends from the tip rearwardly to the base of said drum. This band forms a spiral groove 50 between its convolutions. The band 48 preferably is relatively narrow at the tip of the drum and gradually widens as it progresses toward the base thereof. Similarly, the various convolutions of the band are preferably closer together at the tip of the drum and gradually get farther apart toward the opposite end thereof so that the groove 50 gradually widens toward the drum base.

A hollow conical casing or cover 51 fits over but is spaced from the vaporizing drum 42. This casing consists of inner and outer walls 52 and 53 forming therebetween a chamber 54, in which an electrical heating coil 55 is mounted, said coil being connected to a suitable source of electrical supply in any desired manner, such as by leads 56 which extend through the wall 53. A ring 57 is removably mounted in the concentric opening at the base of the casing 51 between its inner and outer walls. The casing is removably secured to the housing 10 in any suitable manner,

such as by bolts 58 threaded into the front wall 11. If desired, plates 60 may be removably secured to but spaced from the front and rear walls 11 and 12 of the casing 51 in any suitable manner. The spaces between the walls and the plates 60 may be connected to the exhaust system of the engine but it is more desirable to have electrical heating coils 61 in said spaces.

A spiral rib 62, similar to the band 48, is formed on the inner surface of the inner wall 52 of the casing 51, said band forming a spiral groove 63 between its convolutions. The rib 62 is arranged so that it generally overlaps the groove 50 of the drum 42 and, consequently, the rib 48 of said drum generally overlaps the groove 63 of the casing.

The casing 51 forms a conical chamber in which the conical drum 42 rotates. The outer surface of the drum is situated close to the inner surface of the chamber and a conical vaporizing chamber 64 is formed therebetween. The surfaces of the drum and the inner wall of the casing are corrugated, said corrugations being formed by the ribs 48 and 62, so that actually the walls of the vaporizing chamber 64 are corrugated. While the corrugations of the inner wall 52 may be omitted, it is preferable to have said corrugations. The vaporizing chamber communicates with the intake manifold of the engine through the housing 10.

Fuel and air are supplied to the vaporizing chamber 64 at the tip of the vaporizing drum in any suitable manner and one method of doing this is illustrated in Figure 1. A passage 65 extends through the outer end of the casing 51 to the vaporizing chamber and a mixing casing 66 is mounted on the casing 51 over said passage. The casing 66 is formed with a central mixing chamber 67 and with fuel and air chambers 68 and 70, respectively, on each side thereof. Fuel is supplied, preferably by a fuel pump (not shown), to the chamber 68 by a pipe 71. A cover 73 is provided for the chamber 68, through which a stem 74 of a valve 75 rotatably extends, said stem being provided with a disc 76 on its outer end with a pin 77 eccentrically mounted thereon. The valve 75 is seated on the bottom of its chamber by means of a spring 78.

Small, medium and large jets 80, 81 and 82, respectively, are concentrically mounted in the casing 66 and extend through the mixing chamber 67 into the passage 65 of the casing 51. Small, medium and large feed passages 83, 84 and 85, see Figure 3, extend from the fuel chamber 68 to the jets 80, 81 and 82, respectively. An elongated slot 86 is formed in the valve 75, see Figure 4, said slot being relatively large at one end and tapering toward the opposite end. When the valve in the fuel chamber is rotated in the direction of the arrow (see Figure 4), the slot 86 is first brought into registry with the end of the small passage 83, then with the passage 84, and finally with the passage 85. In this way, fuel is supplied to the small jet 80, and then to the medium jet 81, and finally to the large jet 82, the quantity of fuel increasing as the valve advances over the ends of the passages.

Air is supplied to the chamber 70 by a pipe 72 extending from an air storage tank (not shown). A cover 130 is provided for the chamber 70, through which a stem 131 of a valve 132 rotatably extends, said stem being provided with a disc 133 at its outer end with a pin 134 eccentrically mounted thereon. The valve 132 is seated on the bottom of its chamber by means of a spring 135.

An elongated slot 136 is formed in the valve 132 and this slot is the same shape as the slot 86 shown in Figure 4.

A slot 87 is formed in the bottom of the air chamber 70, said slot being substantially the same shape as the slot 136 of the valve in the said chamber. In this case, however, the valve slot 136 normally registers with the slot 87 and when the valve is turned, the one slot is gradually moved out of registry with the other so that the air supply to the chamber 67 is gradually cut off. The air supply pipe 72 is provided with a control valve 88 which is open when the engine is turning over and closed when it is not.

The vaporizing drum 42 is moved axially during rotation in any suitable manner. This movement regulates the volume of the vaporizing chamber 64 by increasing or decreasing said volume in relation to the speed of the engine.

In Figure 1, the volume of the vaporizing chamber is at the maximum when the drum is at rest and suitable means is provided for gradually decreasing said volume as the speed of the engine increases.

A suitable governor 90 is mounted on the shaft 40 within a housing 91 removably secured to the rear wall 12 of the housing 10, the former housing having a flat wall 92 at its outer end with a bearing 93 in which the shaft is journalled. The governor 90 consists of a relatively long sleeve 94 keyed to the shaft 40 and arms 95 pivotally connected to lugs 96 on the outer end of the sleeve, each arm having a weight 97 at its outer end and a cam 98 at its pivot end. The cams 98 are adapted to bear against a movable plate 100 having a circular rib 101 projecting into a circular groove 102 formed in the wall 92, said rib being held away from the bottom of the groove by a coil spring 103. A link 104 connects each arm 95 at a point spaced from its pivot, to lugs 105 on a collar 106 which is slidably mounted on the sleeve 94 adjacent its inner end by means of splines 107 formed in said sleeve. The collar 106 is provided with a flange 108 spaced from the lugs 105 and a coil spring 109 extends between the lugs 96 and 105. A ring 110 is loosely fitted on the collar 106 between its flange and the lugs, and a pair of arms 111 and 140 project outwardly therefrom through elongated openings 112 formed in the housing 91. Links 113 and 141 extending through tubes 114 and 142 which extend through the housing 10, connect the arms 111 and 140, respectively, to the eccentric pins 77 and 131 on the discs 76 and 133 of the valves 75 and 132 so that any lateral movement of the collar 106 rotates said valves.

When the shaft 40 is rotated and the weights 97 of the governor 90 are thrown outwardly by centrifugal force, the cams 98 bear against the plate 100 and shift the shaft with the drum 42 axially toward the casing 51 to reduce the volume of the vaporizing chamber 64. This same operation draws the collar 106 along the sleeve 94 toward the lugs 96. This moves the arms 111 and 140 and the connecting links 113 and 141 to rotate the valves 75 and 132. The fuel valve is set so that it is opened by this movement while the air valve is closed thereby.

In Figure 7, the position of the governor is reversed and the circular groove 102 is formed within the sleeve 31. In this alternative, the operation of the governor draws the vaporizing drum 42 away from the casing 51 to increase the volume of the vaporizing chamber 64. The valves 75

75 are set so as to operate in the same manner as in Figure 1.

In the modification shown in Figure 8, the housing 10 is reduced in size and the spiral partitions 28 and passages 30 are omitted. The fan blades 47 of the drum 42 and the large opening 13 of the wall 11 are omitted but a plurality of smaller openings 114 are formed in said wall in a circle about the shaft 40. In this alternative, the governor may be arranged to move the vaporizing drum in either direction as the speed of the engine increases. Figure 8 illustrates a form of governor for enlarging the volume of the vaporizing chamber. In this governor, a collar 115 keyed to the shaft 40, is provided with lugs 116. Weighted blades 117 are pivoted adjacent one end to the lugs 116 and are formed with the cam surfaces 118 at said end. These blades are connected by links 120 to lugs 121 formed on the inner end of a relatively long sleeve 122 which is slidably mounted on the shaft 40 by means of splines 123, and slidably extends through the end of the housing 91. A coil spring 124 extends between the collar 115 and the sleeve 122 and a wheel 125 having spaced flanges 126 is formed on or fixed to the outer end of said sleeve. The ring 110 is mounted on the wheel 125 and its arms 111 and 140 are connected by the links 113 and 141 to the valves 75 and 132, said valves being set to operate in accordance with the direction of movement of the governor in this form of the invention. This governor not only shifts the vaporizing drum axially, but when the blades 117 are swung outwardly they act in the same capacity as the blades 47 of the other forms of the invention.

In operation, when the engine is first started, the valves 75 are set to admit fuel and air into the passage 65 where they are mixed and the fuel at least partially vaporized. Any one or all the heating coils 45, 55 and 61 may be on. If desired, suitable means may be provided whereby one coil may be used in comparatively mild weather, two in cool weather and three in cold weather. The partially vaporized fuel is blown or forced through the vaporization chamber 64, the spiral passages 30, if these are employed, and through the jet 26 where it is mixed in or above the Venturi passage 20, with air drawn by the suction of the engine through the intake pipe 15 and the passages 24 and 25. This air is preheated if the coils 61 are used.

Referring to Figure 1, the volume of the vaporizing chamber is largest when the engine is just started or is running very slowly. In this case, the air from the pipe 72 blows the vaporized fuel through the device into the intake manifold of the engine. As the speed of the engine is increased, the governor 90 moves the vaporizing drum to reduce the volume of the vaporizing chamber. The device is so constructed that the drum is moved to the position where the volume of the chamber is right for the most efficient vaporization of the fuel when the engine is running at a fair speed. With this arrangement, the engine is supplied with sufficient fuel for starting purposes and then the supply is cut down as the engine warms up for the most economical operation. The governor is arranged so that it permits a certain amount of axial movement of the drum without interfering with its rotation. In other words, the pressure of the air and fuel against the drum will not cause any binding or other trouble during the rotation thereof.

The fuel is vaporized in the vaporizing chamber by heat, centrifugal force and friction. The coils 45 and/or 55 heat the fuel, the drum swirls it around and the corrugations of the drum and the inner wall of the casing break it up by friction. The number of turns or convolutions of the spiral ribs 48 and 62 depends upon the type of fuel for which the generator is designed. Gasoline would not require very many turns while fuel oil would require more. The fuel is completely vaporized when leaving the chamber and the fan blades 47 propel it through the spiral passages 30 where friction and heat from the coils 61, if used, maintain it in this state. The fact that the passages 30 taper outwardly prevents the pressure of the vaporized fuel supplied to the manifold, from being too high. The check valve 27 prevents any backfiring into the space within the ring 22.

The collar 106 moves as the speed of the engine increases to turn the fuel valve 75 through the arm 11, link 113, disc 16 and the eccentric pin 71. This increases the quantity of fuel supplied to the device through one or all the jets 80, 81 and 82. This same movement of the collar 106 turns the air valve 132 gradually to cut off the air supply. When the engine is running faster, this air is not necessary as the drum is running fast enough and the vaporizing chamber is hot enough to ensure complete vaporization of the fuel. The spiral band 48 acts more or less as a fan and it, along with the blades 47, ensure a sufficient volume of vaporized fuel or gas being supplied to the Venturi passage 20. From this it will be seen that the suction of the engine is not used to vaporize the fuel but to draw it through the generator.

In Figure 7, the governor increases the volume of the vaporizing chamber as the speed of the engine increases. Although this is not believed to be as efficient as the form of the invention just described, it is very useful. The governor prevents the air or fuel pressure from interfering with the rotation of the drum and it enlarges the vaporizing chamber to permit a free passage of the fuel therethrough.

This form of construction may be employed, for instance, in the case where heavy hydrocarbons are used as fuels where it is desirable when starting the engine to concentrate the heat in the vaporizing chamber and to subject the fuel to the most rigorous mechanical treatment for vaporizing the fuel during which time the injection of air assists the passage of the fuel through the vaporizing chamber. At higher speeds, however, an increase in the size of the chamber is desirable to permit free flow of the fuel in accordance with the requirements of the engine and when the air injection to the vaporizing chamber is cut off.

In Figure 8, the spiral passages 30 have been omitted. These passages are not absolutely necessary but they act as a storage reservoir to supply fuel to the engine on sudden demand due to acceleration and they check the pressure of the fuel. In this alternative, the vaporized fuel passes from the vaporizing chamber through the openings 114 into the housing 10 and the blades 117 stir it up and direct it to the jet 26. The faster the shaft 40 is rotated, the further out the blades 117 swing resulting in their fanning capacity being increased as the demand for fuel increases. As stated before, the setting of this governor may be the same as in either Figure 1

or 7 and the remainder of the generator acts as described above.

Referring again to Figure 1, the governor aids acceleration of the engine at all times. For example, when the engine is running at a certain speed and it is suddenly accelerated, the governor more or less lags behind the acceleration, thus permitting a relatively free flow of fuel through the vaporizing chamber until the engine reaches the required speed, at which time the weights of the governor have moved outwardly to their new positions in relation to the speed, to adjust the size of the vaporizing chamber to harmonize with this speed.

The partially vaporized fuel expands when it enters the vaporizing chamber. This increases the pressure in the chamber but the corrugations of the drum and the inner wall of the surrounding casing prevent the gas from escaping too rapidly from the chamber and, in any case, the taper of the spiral passages 30 relieve any excess pressure that may accumulate in the generator.

From the above, it will readily be seen that a gas generator for internal combustion engines has been provided, which automatically adjusts itself to the speed of its engine, which operates in an efficient manner, and which does not require the suction of the engine for vaporizing purposes.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. A gas generator, comprising a casing, a drum rotatably mounted in the casing, a vaporizing chamber formed between the drum and the casing, said chamber having a discharge outlet, means for rotating the drum, means for moving the drum back and forth in the chamber to regulate the size of the vaporizing chamber in relation to the speed of rotation of said drum, and means for supplying fuel and air to the chamber wherein said fuel is vaporized.

2. A gas generator, comprising a casing, a drum rotatably mounted in the casing, a vaporizing chamber formed between the drum and the casing, said chamber having a discharge outlet, means for heating the chamber, means for rotating the drum, means for moving the drum back and forth in the chamber to increase and decrease the size of the vaporizing chamber in relation to the speed of rotation of said drum, and means for supplying fuel to the vaporizing chamber wherein said fuel is vaporized, and means for selectively supplying air under pressure to said chamber.

3. A gas generator, comprising a casing, a drum rotatably mounted in the casing, a vaporizing chamber formed between the drum and the casing, said chamber having a discharge outlet, means for heating the chamber, means for rotating the drum, means for moving the drum back and forth in the chamber to increase and decrease the size of the vaporizing chamber in relation to the speed of rotation of said drum, means for supplying fuel to the chamber wherein said fuel is vaporized, means for selectively supplying air under pressure to said chamber,

and means for varying the quantity of the air in relation to the speed of the engine.

4. A gas generator comprising a casing having a conical chamber formed therein, a conical drum rotatably mounted in the casing, a vaporizing chamber formed between the drum and the casing, said chamber having a discharge outlet, means for heating the chamber, means for rotating the drum, means for moving the drum back and forth in the chamber to increase or and decrease the size of the vaporizing chamber in relation to the speed of rotation of said drum, and means for supplying fuel to the vaporizing chamber wherein said fuel is vaporized, and means for selectively supplying air under pressure to said chamber.

5. A gas generator comprising a casing having a conical chamber formed therein, a conical drum rotatably mounted in the casing, a vaporizing chamber formed between the drum and the casing, said chamber having a discharge outlet, means for rotating the drum, means for moving the drum back and forth in the chamber to increase and decrease the size of the vaporizing chamber in relation to the speed of rotation of said drum, means for supplying fuel to the chamber wherein said fuel is vaporized, means for selectively supplying air under pressure to said chamber, and means for varying the quantity of the air in relation to the speed of the drum.

6. A gas generator comprising a casing having a conical chamber formed therein, a conical drum rotatably mounted in the casing, a vaporizing chamber formed between the drum and the casing, said chamber having a discharge outlet, corrugations formed on the surface of the drum and on the inner surface of the vaporizing chamber, means for rotating the drum at variable speeds, means for moving the drum to increase the size of the vaporizing chamber when the speed of the drum increases, means for supplying fuel to the vaporizing chamber wherein said fuel is vaporized, and means for selectively supplying air under pressure to said chamber.

7. A gas generator comprising a casing having a conical chamber formed therein, a conical drum rotatably mounted in the casing, a vaporizing chamber formed between the drum and the casing, said chamber having a discharge outlet, means for heating the chamber, corrugations formed on the surface of the drum and on the inner surface of the vaporizing chamber, means for rotating the drum at variable speeds, means for moving the drum to increase the size of the vaporizing chamber when the speed of the drum increases, means for supplying fuel to the vaporizing chamber wherein said fuel is vaporized, means for selectively supplying air under pressure to said chamber, and means for varying the quantity of the air in relation to the speed of the drum.

8. A gas generator comprising a casing having a conical chamber formed therein, a conical drum rotatably mounted in the casing, a vaporizing chamber formed between the drum and the casing, said chamber having a discharge outlet, corrugations formed on the surface of the drum and on the inner surface of the vaporizing chamber, means for rotating the drum at variable speeds, means for moving the drum to decrease the size of the vaporizing chamber when the speed of the drum increases, means for supplying fuel to the vaporizing chamber wherein said fuel is vaporized, and means for selectively supplying air under pressure to said chamber.

9. A gas generator comprising a casing having

5 a conical chamber formed therein, a conical drum rotatably mounted in the casing, a vaporizing chamber formed between the drum and the casing, said chamber having a discharge outlet, means for heating the chamber, corrugations formed on the surface of the drum and on the inner surface of the vaporizing chamber, means for rotating the drum at variable speeds, means for moving the drum to decrease the size of the vaporizing chamber when the speed of the drum increases, means for supplying fuel to the vaporizing chamber wherein said fuel is vaporized, means for selectively supplying air under pressure to said chamber, and means for varying the quantity of the air in relation to the speed of the drum.

10. A gas generator comprising a casing having a conical chamber formed therein, a conical drum rotatably mounted in the casing, a vaporizing chamber formed between the drum and the casing, said chamber having a discharge outlet, means for heating the chamber, corrugations formed on the surface of the drum and on the inner surface of the vaporizing chamber, means for rotating the drum at variable speeds, means for moving the drum to decrease the size of the vaporizing chamber when the speed of the drum increases, means for supplying fuel to the vaporizing chamber wherein said fuel is vaporized, means for selectively supplying air under pressure to the chamber, and means for decreasing the quantity of the air as the speed of the drum increases.

11. A gas generator comprising a vaporizing chamber having a discharge outlet, a drum rotatably mounted in the chamber, the outer surface of the drum being spaced from the inner surface of the chamber, corrugations formed on both said surfaces, means for rotating the drum at variable speeds, means for moving the drum towards and away from the inner surface of the chamber, and means for supplying fuel to the chamber, said fuel being vaporized and broken up in the vaporizing chamber.

12. A gas generator comprising a conical vaporizing chamber having a discharge outlet, a conical drum rotatably mounted in the chamber, the outer surface of the drum being spaced from the inner surface of the chamber, corrugations formed on both said surfaces, means for rotating the drum at variable speeds, means for moving the drum towards and away from the inner surface of the chamber, and means for supplying fuel to the chamber, said fuel being vaporized and broken up in the vaporizing chamber.

13. A gas generator comprising a conical vaporizing chamber having a discharge outlet, a conical drum rotatably mounted in the chamber, the outer surface of the drum being spaced from the inner surface of the chamber, corresponding corrugations formed on both said surfaces, means for rotating the drum at variable speeds, means for moving the drum towards and away from the inner surface of the chamber, means for supplying fuel to the chamber adjacent the tip thereof, and means for selectively supplying air under pressure to the fuel before it enters the chamber at least partially to vaporize the fuel, said fuel being further vaporized and broken up in the vaporizing chamber.

14. A gas generator comprising a conical vaporizing chamber having a discharge outlet, a conical drum rotatably mounted in the chamber, the outer surface of the drum being spaced from the inner surface of the chamber, corresponding

corrugations formed on both said surfaces, means for rotating the drum at variable speeds, means for moving the drum towards and away from the inner surface of the chamber, means for supplying fuel to the chamber adjacent the tip thereof, means for selectively supplying air under pressure to the fuel before it enters the chamber at least partially to vaporize the fuel, and means for heating the fuel as it passes through the chamber, said fuel being further vaporized and broken up in the vaporizing chamber.

15. A gas generator comprising a housing having a discharge outlet, a vaporizing chamber communicating at its base with the interior of the housing centrally thereof, a drum rotatably mounted in the chamber, the outer surface of said drum being spaced from the inner surface of the chamber, corrugations formed on both said surfaces, means for rotating the drum at variable speeds, means for moving the drum towards and away from the inner surface of the chamber, a plurality of spiral passages in the housing extending outwardly from the central portion thereof, and means for supplying fuel to the chamber, said fuel passing from the chamber through the spiral passages and out of the generator.

16. A gas generator comprising a housing having a discharge outlet, a conical vaporizing chamber communicating at its base with the interior of the housing centrally thereof, a conical drum rotatably mounted in the chamber, the outer surface of the drum being spaced from the inner surface of the chamber, corresponding corrugations formed on both said surfaces, means for rotating the drum at variable speeds, means for moving the drum towards and away from the inner surface of the chamber, a plurality of spiral passages in the housing extending outwardly from the central portion thereof, means for supplying fuel to the chamber adjacent the tip thereof, and means for selectively supplying air under pressure to the fuel before it enters the chamber at least partially to vaporize the fuel, said fuel passing from the chamber through the spiral passages and out of the generator.

17. A gas generator comprising a housing having a discharge outlet, a conical vaporizing chamber communicating at its base with the interior of the housing centrally thereof, a conical drum rotatably mounted in the chamber, the outer surface of the drum being spaced from the inner surface of the chamber, corresponding corrugations formed on both said surfaces, means for rotating the drum at variable speeds, means for moving the drum towards and away from the

inner surface of the chamber, a plurality of spiral passages in the housing extending outwardly from the central portion thereof, means for supplying fuel to the chamber adjacent the tip thereof, means for selectively supplying air under pressure to the fuel before it enters the chamber at least partially to vaporize the fuel, means for heating the fuel as it passes through the chamber, and means for supplying additional heat to the fuel as it passes through the spiral passages of the housing.

18. A device according to claim 15 in which the spiral passages are tapered with their entrances smaller than their outlets.

19. A device according to claim 15 in which the drum is provided with a plurality of fan blades projecting into the housing adjacent the entrances of the spiral passages, said blades being adapted to assist in moving the vaporized fuel through the device.

20. A gas generator comprising a conical vaporizing chamber having a discharge outlet, a conical drum mounted upon a shaft in the chamber, said shaft extending outwardly from the chamber, means for rotating the shaft and drum at variable speeds, the outer surface of the drum being spaced from the inner surface of the chamber, corrugations formed on both said surfaces, a governor mounted on the shaft adapted to move the drum towards and away from the inner surface of the chamber with variations in the speed of the drum, valve means for supplying fuel to the chamber, and means connecting the governor to the valve means whereby said means is operated to vary the fuel supply when the speed of the drum is changed.

21. A gas generator comprising a conical vaporizing chamber having a discharge outlet, a conical drum mounted upon a shaft in the chamber, said shaft extending outwardly from the chamber, means for rotating the shaft and drum at variable speeds, the outer surface of the drum being spaced from the inner surface of the chamber, corrugations formed on both said surfaces, a governor mounted on the shaft adapted to move the drum towards and away from the inner surface of the chamber with variations in the speed of the drum, valve means for supplying fuel to the chamber, valve means for selectively supplying air under pressure to the chamber, and means for connecting the governor to each of said valve means, said governor being adapted to increase the fuel supply and decrease the air supply as the speed of the drum increases.
